DOOR

Roy D. B. Moynahan, Birmingham, Mich.

Application November 22, 1939, Serial No. 305,711

16 Claims.

(Cl. 189—46)

This invention relates to a door of the type in which a strong frame is covered by an ornamental sheathing.

A particular feature of the construction resides in the fact that the sheathing sections are so shaped as to permit their production by extrusion, thus insuring sections that are dense, free from porosity, and that require only a minimum of finishing operations.

Another feature of the invention is that the sheathing parts are so arranged as to conceal all the fastening means used to secure the sheathing to the frame.

These and other objects and advantages of the invention will become apparent as the description proceeds.

While one structural embodiment of the invention is disclosed herein for purposes of illustration, it should be understood that various changes may be made in the construction shown without departing from the spirit of the invention.

In the drawings:

Fig. 1 is an elevation partly in section of a door embodying the invention.

Fig. 2 is a section on line 2—2 of Fig. 1.

Fig. 3 is a section on line 3—3 of Fig. 1.

Fig. 4 is an enlarged detail section showing the construction at the upper end of Fig. 2.

Fig. 5 is an enlarged detail section showing the construction at the lower end of Fig. 2.

Figs. 6 to 11 inclusive are perspective views of the non-ferrous sheathing sections.

A door constructed according to the present invention comprises in general a framework, formed of some strong material such as steel, covered with sheathing of an ornamental and protective material, such as aluminum.

The framework of the door illustrated includes side stiles 10 and 11, which are hollow steel sections. An upper rail 12, also a hollow steel section, is welded to the side stiles forming the lower rail; a solid steel bar 13 is welded across the lower ends of the side stiles; and a steel channel bar 14 is welded between them a short distance above the bottom of the door. This framework can of course be varied in design and can be made as strong and rigid as required for the particular installation.

The side stiles 10 and 11 and the upper rail 12 are all covered by sheathing which includes a substantially U-shaped section 15 shown in perspective of Fig. 6. The side walls of this section carry inclined ribs 16 near the closed end, and the lower ends of its walls have inwardly offset

flanges 17. Flanges 18, which project from the closed end, have dovetail recesses 19 for a purpose to be described later. This section 15 is extruded in the shape shown, and pieces are cut of a length suitable for covering the frame members 10, 11 and 12. These pieces are then slipped over the outside of the stiles, and secured to them by the screws 20 which fit into countersunk holes in the base of the section 15. (See Fig. 4.)

The inner wall of the stiles 10, 11 and rail 12, is covered by pieces of glass-carrying strip 21, shown in perspective in Fig. 7, which have flanges 22 that closely fit over the flanges 17 of the section 15. Machine screws 23 are countersunk in a channel groove 24 and engage the stiles 10 and 11 and rail 12 to hold the strips 21 in place.

With the sections 15 and strips 21 in place the frame members are completely covered by the extruded sheathing. The inclined ribs 16 space the walls of section 15 from the hollow framework a sufficient distance to permit the flanges 17 to project inwardly, engaging the frame and extending under the flanges 22 of the strip 21. After these parts have been thus secured together, cover strips 25 of the shape illustrated in Fig. 9 are slipped over the outer faces of the section 15, bevelled edges 26 of the cover strips engaging in the dovetail grooves 19 of the sections 15.

The sheathing for the lower part of the door includes two removable kick plates 27 which, as shown in Fig. 11, are extruded with an inwardly projecting flange 28 that cooperates with the upper edge of the body of the plate to form a groove 29. A straight flange 30 projects inwardly a short distance above the lower end of the plate.

The upper ends of the kick plates are held by a kick plate rail 31, which is extruded (see Fig. 10) in a substantially H shape with inturned flanges 32 attached to the upper ends of the side walls. This kick plate rail is placed above the channel bar 14 (Fig. 5), secured thereto by set screws 33, and since it is of the same overall thickness as the sections 15, it cooperates with these sections to form a smooth framing for the glass opening.

The two kick plates 27 are placed on opposite sides of the door with their lateral ends overlying the sheathing sections 15 which cover the vertical stiles; the grooves 29 fit over the lower edges of the kick plate rail 31, and the two flanges 30 meet on the bottom side of the frame bar 13 to which they are attached by screws 34. This construction permits the easy removal and replacement of worn kick plates but conceals the means used to secure them in place.

The upper side of the kick plate rail 31 is capped by a glass-carrying rail 21 of the type previously described, which fits over the flanges 32 of the rail 31; and is held to the rail 30 by screws 35.

After the glass-carrying rails 21 are in place around the four sides of the light opening, the glass 38 may be set in place with its edges fitting over the channel grooves 24 and one side resting against the curved retainer 37 which projects from one side of the glass-carrying strip 21. Separate glass-retainer strips 38 of the shape shown in Fig. 8 are then placed as shown in Fig. 4 and screwed to the rails 21.

Wherever hardware such as hinges and locks is to be attached to the vertical edges of the door the cover strips 25 are cut away so that the hardware fittings are flush with the outer face of these cover strips. The hardware is directly attached to the steel framework, which is so rigid as to require no special reinforcing for the hardware.

The construction above described results in a door that is strong and rigid, while having a smooth exterior devoid of any exposed screw or rivet heads, all fastening means being concealed except the few screws used to retain the glazing strips 38 in place.

As the result of the principles of construction used in this door all parts can be kept in stock machined to standard widths and thicknesses, subject to being cut to required lengths for the production of a door of any desired size.

It will be clear to those skilled in the art that the frame may be made of steel or any preferred strong material, and that the sheathing sections may be extruded or molded of any suitable metal or plastics.

If the sheathing sections are extruded from aluminum they may be given a treatment known as "anodizing," which gives the aluminum an attractive and durable surface. The design is such that all of the aluminum parts can be anodized before final assembly. This is advantageous because an aluminum product cannot be anodized after any metals or substances other than aluminum have been assembled with the aluminum.

I claim:

1. In a door of the type in which a frame is covered by a sheathing, the improvement which comprises, a frame member, a unitary homogeneously integral sheathing section having a substantially U-shaped cross section fitted over the outer edge and sides of the frame member, and a glass-carrying cover strip interfitted with the edges of the sheathing section.

2. A structure as specified in claim 1 in which the U-shaped sheathing section has adjacent its closed end ribs projecting inwardly engaging the sides of the frame member spacing the walls of the U-shaped section from the frame member, and at its open end flanges offset inwardly engaging the sides of the frame member and interfitting with the glass-carrying cover strip.

3. A structure as specified in claim 1 in which the U-shaped sheathing section is secured to the frame member by fastening means passing through the closed end of the sheathing section, and a cover strip has dovetailed engagement with the sheathing section and conceals the fastening means.

4. In a door of the type in which a ferrous frame is covered by a sheathing of non-ferrous material, the improvement which comprises, a ferrous frame member, a unitary homogeneously

integral sheathing section of extruded non-ferrous metal having a substantially U-shaped cross section fitted over the outer edge of the frame member, and a glass-carrying cover strip interfitting with the edges of the sheathing section, the sheathing section and the cover strip cooperating to completely inclose the frame member.

5. A structure as specified in claim 4 in which the U-shaped sheathing section has adjacent its closed end ribs projecting inwardly engaging the sides of the frame member spacing the walls of the U-shaped section from the frame member, and at its open end flanges offset inwardly engaging the sides of the frame member and interfitting with the glass-carrying cover strip.

6. A structure as specified in claim 4 in which the U-shaped sheathing section is secured to the frame member by fastening means passing through the closed end of the sheathing section, and a cover strip has dovetailed engagement with the sheathing section and conceals the fastening means.

7. In a door of the type in which a frame is covered by a sheathing, the improvement which comprises, a frame member, a sheathing section fitted over part of the frame, flanges extending from the sheathing section and having undercut grooves, fastening means securing the sheathing section to the frame member, and a cover strip engaged in the said undercut grooves and concealing the fastening means.

8. A structure as specified in claim 7 in which another sheathing member has interfitting engagement with the said sheathing section.

9. In a door of the type in which a ferrous frame is covered by a sheathing of non-ferrous material, the improvement which comprises, a ferrous frame member, a sheathing section of non-ferrous metal fitted over part of the ferrous frame, flanges extending from the sheathing section and having undercut grooves, fastening means securing the sheathing section to the ferrous frame member, and a cover strip engaged in the said undercut grooves and concealing the fastening means.

10. A structure as specified in claim 9 in which another sheathing member has interfitting engagement with the said sheathing section.

11. In a door of the type in which a frame is covered by a sheathing, the improvement which comprises, a kick plate rail, a lower rail, a pair of kick plates, each kick plate having a flange homogeneously integral therewith and extending inwardly near its bottom edge, each of the kick plates having its upper edge interfitting with the kick plate rail and having its inwardly extending flange fastened in direct contact with the lower rail of the frame.

12. In a door of the type in which a ferrous frame is covered by a sheathing of non-ferrous material, the improvement which comprises, a kick plate rail, a lower rail, a pair of kick plates of non-ferrous metal, each kick plate having a flange homogeneously integral therewith and extending inwardly near its bottom edge, each of the kick plates having its upper edge interfitting with the kick plate rail and having its inwardly extending flange fastened in direct contact with the lower rail of the ferrous frame.

13. In a door of the type in which a frame is covered by a sheathing, the improvement which comprises, vertical stile members covered with sheathing, a horizontal kick plate rail having its sides flush with the sheathing of the vertical stile members, a pair of kick plates, each kick plate

having a flange extending inwardly, each kick plate being secured in place with its upper edge interfitted with the kick plate rail, with its lateral ends overlying the sheathing of the vertical stile members, and with its inwardly extending flange 5 fastened to part of the frame.

14. A structure as specified in claim 13 in which the kick plate rail is of substantial H shape in cross section and is secured by fastening means to a member of the frame, the upper edges 10 having inwardly offset flanges which are inter-fitted with a glass-carrying strip.

15. In a door of the type in which a ferrous frame is covered by a sheathing of non-ferrous material, the improvement which comprises, 15 vertical stile members covered with sheathing of non-ferrous material, a horizontal kick plate rail

of non-ferrous metal having its sides flush with the sheathing of the vertical stile members, a pair of kick plates of non-ferrous metal, each kick plate having a flange extending inwardly, each kick plate being secured in place with its upper edge interfitted with the kick plate rail, with its lateral ends overlying the sheathing of the vertical stile members, and with its inwardly extending flange fastened to part of the ferrous frame.

16. A structure as specified in claim 15 in which the kick plate rail is of substantial H-shape in cross section and is secured by fastening means to a member of the ferrous frame, the upper edges having inwardly offset flanges which are inter-fitted with a glass-carrying strip.

ROY D. B. MOYNAHAN.
